UNITED STATES PATENT OFFICE.

JOHN JOHNSTON, OF NEW YORK, N. Y.

ASH-COLLECTING APPARATUS.

1,176,832.

Specification of Letters Patent. Patented Mar. 28, 1916.

Application filed November 30, 1914. Serial No. 374,818.

To all whom it may concern:

Be it known that I, JOHN JOHNSTON, a British subject, residing at New York, N. Y., have invented certain new and useful Improvements in Ash-Collecting Apparatus, of which the following is a specification.

My present invention comprises an improved apparatus for collecting ashes, and has among its objects to provide a simple, durable and efficient form of motor driven apparatus; and the invention includes the novel features of construction and arrangement and combination of parts hereinafter described and particularly pointed out in the appended claims.

An apparatus embodying my invention is illustrated in the accompanying drawings, in which—

Figure 1 is a side elevation of the apparatus; Fig. 2 is a plan view; and Fig. 3 is a detail sectional elevation. Fig. 4 is a detail view.

Referring by reference characters to this drawing, the letter A designates a motor vehicle which, except as hereinafter specified, may be of the ordinary or any desired construction, and may be propelled in any suitable manner.

As the propelling mechanism forms no part of the invention, I have not deemed it necessary to illustrate the same herein.

In rear of the driver's seat is located a transverse platform B upon which is mounted an electric motor 1 deriving its current from any suitable source of supply. This may be a storage battery, or if the vehicle is of the "gas electric" type, the current may be furnished by a generator driven by the gas engine. This motor, by means of suitable sprockets and chains indicated by the numerals 2 to 6 inclusive, drives a shaft 8 around which passes an elevator belt 9 which carries one or more ash can lifting shelves or flights 10 of ordinary construction, the belt being supported at its upper end by pulleys 11 mounted on a shaft journaled in the casing or housing 19 which extends upwardly from the platform.

I aim to take filled ash cans, place them in a closed receptacle upon an elevating device, lift the cans to a dumping position where the ashes are discharged upon a chute leading to a receptacle carried by the vehicle, after which the can is reversed in position automatically and delivered right side up to be utilized for refilling and elevating

to the point of discharge. This avoids the labor of lifting the filled can manually to any material height, and also insures that the dumping shall take place in a closed 60 space, preventing the flying clouds of ash dust so objectionable with the ordinary methods of handling ashes. Downward movement of the inverted can is interrupted by the stop 22 and further movement is continued after the knock-off lever 23 has tilted the bottom of the can forward and down the inclined plane 24 of the forward portion of the casing 19. This tilting action is caused by the force of the impact of the 70 can on the stop 22, which forms, in combination with the lever 23, a bell crank action.

In operation the full can C is set on the bracket 10 (see position *x* in Figs. 1 and 3). Through the motive power (Fig. 3) this 75 bracket or shelf is raised, the full can remaining in its upright position until the position *y* is reached. At that point the top of the can is tilted toward the right hand side of the machine until it is completely inverted to the position shown at *m*. The rear edge of the top of the inverted can strikes the stop 22, causing the lever 23 to push the inverted bottom of the can forward and downwardly until it reaches the 85 upright position shown at *n* in Figs. 1 and 3. From this position the can drops along the inclined bottom 24 of the forward end of the casing 19 to the portion 19^a of the casing in position to be removed for refilling. 90

As shown in Fig. 2, the empty can is shown in dotted lines at the right of the casing 19^a, and the full can at the left of the casing 19 and in position to be lifted by the elevator, Fig. 1 showing doors which permit the taking out of the empty can from the part 19^a of the casing and inserting it in the door to the left thereof on the shelf of the elevator belt. The filled can is carried up by the elevator and dumped, the ashes 100 being directed into the receptacle C by the chute shown in dotted lines in Fig. 1, and after the tilting action the can is reversed in position as shown in Fig. 1 and is directed to the position shown to the right of Fig. 2 105 by the inclined wall shown in dotted lines in Fig. 3. Yielding springs 24 are provided in the lower part of this casing to prevent the can being injured by the fall, and from this position the can may be removed 110 through a suitable door provided for the purpose.

The ash receptacle C is mounted to slide on the body, preferably on anti-friction rollers c, so that it may be conveniently dumped when full, and has a rear door or hinged cover C'.

5 Within the ash receptacle C is located a spreader comprising a pair of endless chains 21 passing over pulleys 21^a, 21^b, and provided with slats or flights to effect the even 10 spreading of the ashes within the receptacle and prevent their piling up at one end. The pulleys at 21^b are drive pulleys, and are mounted on a shaft having a worm wheel 15 driven by a worm 14 which has its shaft 14^a 15 projected through the end of the casing, and provided with a square end to engage a square opening in the shaft of a pulley 13 which is driven by the motor 1. Thus as 20 the ash receptacle C is slid back and forth, the shaft and pulley are automatically engaged and disengaged.

25 The motion of the elevator 9 is very slow, and furthermore it will be understood that any suitable means for starting and stopping the motor may be used.

At the rear of the vehicle or truck I provide a combined sweeping and elevating means which is preferably in the form of a truck frame D having two supporting 30 wheels d and a steering wheel d' detachably connected by a short tongue E with the rear of the motor vehicle. This truck D carries a water tank D' connected with a suitable sprinkler F and also a motor G which, 35 through suitable gearing, drives a sweeper H. This sweeper sweeps the dust into a

dust pan from which it is carried by scraper flights I to the elevator leg J which delivers it into the receptacle C, preferably through a suitable opening in door C'.

40 Any suitable means may be provided for reversing the movement of the spreader according to which end the receptacle is being filled at.

Having thus described my invention what 45 I claim is:

1. In combination with an ash collecting receptacle, a housing, a chute from said housing delivering into the receptacle, elevating means adapted to receive and elevate⁵⁰ a filled ash can, and means for dumping the same, and means for moving the can laterally to automatically reverse for reuse, substantially as described.

2. In combination a motor vehicle having 55 a collection receptacle, a housing at one end of said receptacle, having a chute delivering into said receptacle, means for elevating ash cans and inverting them to empty the contents upon the chute, said housing having a 60 separate compartment for receiving the empty can and means independent of the elevating action for righting the empty can and delivering it to said receiving compartment.

65 In testimony whereof I affix my signature in presence of two witnesses.

JOHN JOHNSTON.

Witnesses:

JOHN A. FAHEY,
JOHN GROOM.
